UNITED STATES PATENT OFFICE.

ALBERT BAREIS, OF ST. LOUIS, MISSOURI, ASSIGNOR, BY DIRECT AND MESNE ASSIGNMENTS, OF FIVE-SIXTHS TO JOHN JOHNSON, ALPHINIE MARTINI, AND ANNA MARTINI, OF SAME PLACE.

PIPE-WRENCH.

SPECIFICATION forming part of Letters Patent No. 478,948, dated July 12, 1892.

Application filed April 6, 1892. Serial No. 428,007. (No model.)

To all whom it may concern:

Be it known that I, ALBERT BAREIS, of the city of St. Louis and State of Missouri, have invented certain new and useful Improvements in Pipe-Wrenches, of which the following is a full, clear, and exact description, reference being had to the accompanying drawings, forming a part hereof.

My invention relates to improvements in pipe-wrenches; and it consists in the novel arrangement and combination of parts, as will be more fully hereinafter described, and designated in the claim.

In the drawings, Figure 1 is a perspective view of my complete invention having a portion of the handle broken away; and Fig. 2 is a vertical longitudinal section of the same, showing the manner of securing the tooth jaws or plates to the wrench proper.

The object of my invention is to provide a simplified construction in pipe-wrenches which in outward appearance resembles and is known as the "alligator-jaw," but differs materially from said pipe-wrench in a manner as hereinafter more fully described.

Referring to the drawings, 1 represents my complete wrench, which is provided with a jaw 2 and a handle 3 for manipulating said wrench back and forth upon the pipe to be turned, the same sliding in one direction and gripping in the opposite direction.

4 represents the upper extension or portion of the jaw 2, which is provided with an inner flat surface 5, and said surface provided with a semicircular depression 6 about its medium portion, as best shown in Fig. 2.

7 represents a ratchet-tooth plate, which is preferably constructed of steel, the said teeth formed in the proper direction in order to take a hold of the surface of the pipe when the wrench is turned in the direction as shown in the arrow in Fig. 2.

8 represents a perforated rounded extension, the size of which corresponds with the size of the circular depression 6 and is adapted to be located therein, in which instance a rivet or bolt 9 is passed through the extension 4 of the wrench and said rounded extension 8, whereby the said plate is rigidly attached to the jaw 2 of the wrench.

10 represents the lower extension of said jaw, the inner surface of which is flat, as shown at 11, and formed in said surface about its medium portion is an elongated depression 12.

13 represents a second plate, which is also constructed of steel and is provided with ratchet-teeth, which are formed thereon in an opposite direction to those formed on the plate 7. 14 represents a staple-shaped extension, which is formed with the said plate 13 and is adapted to be received by the elongated depression 12 when the said plate is in a position as shown in Fig. 2. The said plate 13 is constructed to slide or move in two directions, and its movement is limited in one direction by the shoulder 15, forming the throat 16 of the jaw, and is limited in movement in the opposite direction by the rivet or bolt 17, which is passed through the extension 14 of the wrench and the staple-shaped extension 14 of the movable jaw 13, all of which is best shown in Fig. 2.

When the wrench is first applied to a pipe, the same is moved in an opposite direction to that shown by arrow in Fig. 2 upon the said pipe, causing the plate 13 to assume the position as shown in the drawings; but when the said pipe is turned in the direction as shown in the drawings the said plate will slightly move toward the shoulder 15 and firmly grip the pipe to be turned.

In turning a pipe the wrench is preferably moved back and forth, sliding in one direction and binding in the opposite direction, the movable plate 13 moving back and forth as the said wrench is operated.

The wrench as constructed is also adapted to be applied to pipes of various sizes, working equally as well on small pipes as large ones.

Having fully described my invention, what I claim is—

A pipe-wrench consisting of a handle 3, a jaw 2, composed of extensions 4 and 10, a semicircular depression 6, formed in the said extension 4, a ratchet-tooth plate 7, provided with a rounded projection 8, adapted to be received by the said depression, a rivet or bolt 9, passed through said extension 4 and projection 8, a movable ratchet-tooth plate 13, 95

provided with a staple-shaped extension 14, an elongated depression 12, formed in the said extension 10, and a rivet or bolt 17, passed through the said extension and the staple-shaped extension 14 for limiting the movement of the said jaw 13 in one direction, substantially as described.

In testimony whereof I affix my signature in presence of two witnesses.

ALBERT BAREIS.
